UNITED STATES PATENT OFFICE

2,426,851

CLOTHES-WASHING MACHINE

Philip B. Winston, Fairfax, Va.

Application July 11, 1944, Serial No. 544,338

3 Claims. (Cl. 68—148)

1

This invention relates to washing machines and has more specific reference to a type which is expressly, but not necessarily, adapted for washing clothes and apparel, and as will be evident from the drawings and the description thereof, it is my primary aim to generally improve upon known patented and marketed clothes washing machines, this by way of certain novel refinements and features of distinction hereinafter to be revealed.

Broadly and briefly stated, the improved washing machine is characterized by a portable tub provided with a removable lid or cover, there being an apertured rapidly driven rotatable basket confined in said tub, said basket having at its center an upstanding stationary water delivery tube, the latter partially perforated so that water jets issue radially therefrom, the water acting on the clothes and being whirled out through the apertures in the basket by centrifugal force brought into play by the spinning of said basket.

More specifically, novelty is predicated upon an apertured basket having spider means at its top, said means having a central toothed propulsion collar, the teeth thereof meshing with a co-acting pinion mounted atop a rotary motion transmitting shaft.

An essential phase of novelty is predicated upon the central stationary upstanding water delivery tube, this partially perforated at its top portion, the motion transmitting shaft extending axially up through said tube, and said shaft being formed with a spiral screw pump, the latter for forcibly feeding the water in to be sprayed out through the apertured portion, said pump serving also to draw the water out, whereby to provide a single pump for filling and operating the machine and also subsequently withdrawing the water from the machine for drainage.

Of outstanding importance is the pump arrangement characterized by a single valved branch pipe located beneath the bottom of the tub, said pipe to accommodate a hose which, as stated, may be employed to first feed the water into the machine and may be then secondarily employed to draw the water out from the machine to be drained into the stationary wash tub or elsewhere.

Other features and advantages will become more readily apparent from the following description and the accompanying illustrative drawings.

In the drawings, wherein like numerals are employed to designate like parts throughout the same:

2

Figure 1 is a view partly in section and partly in elevation of a clothes washing machine constructed in accordance with the principles of the instant invention, the same being set up for use.

Figure 2 is a central horizontal section through the tub and basket, the section being taken approximately on the plane of the line 2—2 of Figure 1 looking in the direction of the arrows.

Figure 3 is a fragmentary section taken approximately on the plane of the line 3—3 of Figure 1.

Figure 4 is a fragmentary elevational view of the interior of the relatively stationary tub.

Figure 5 is a fragmentary elevational view of the filling and draining pipe.

Referring now to the drawings by distinguishing reference numerals it will be observed that the relatively stationary tub is indicated at 6 and the removable substantially fluid-tight cover

20 or lid at 7, the latter having a venting port 8. The tub is supported on legs 9 having casters 10. A horizontal cross-piece 11 carried by the leg structure and located beneath the bottom of the tub serves to support a suitably constructed cen-

25 trally arranged electric motor 12. A water delivering and draining tube 13 has its lower end attached to the motor, rises therefrom, and extends up through the bottom of the tub, having fluid-tight connection with the tub, and also hav-

30 ing a bearing 14 for the adjacent portion of the motion transmitting motor driven shaft 15. The lower portion of the tube is imperforate as at 16, except at the points 17, these perforations forming water return ports and emptying into the tub.

35 The upper half portion of the tube 13 is provided with a multiplicity of apertures 18 for distributing and issuing the water jets, as is obvious. It will be noticed that the upper end of the motion transmitting shaft 15 extends above the

40 delivery and distributing tube 16 where it is provided with a collar 15a and a beveled driving pinion 19 in mesh with teeth on another collar or ring 20 carried by the radial spider arms 21, the latter connected with the wall or rim of the apertured clothes basket 22.

45 The latter is provided with a relatively large opening 23 surrounding the adjacent portion of the tube just above the discharge ports 17. Annular tracks 24 and 25 are interposed between the bottom of the tub and the bottom of the basket and ball-bearings 26

50 form a raceway between the tracks, whereby to provide a satisfactory support and drive for said basket. The numerals 27 designate vertical circumferentially spaced ribs mounted on the in-

terior of the tub in close proximity to the wall of the basket.

I next direct attention to the combined two-way delivery and discharge pipe 28 which is located beneath the bottom of the tub and has a suitable threaded connection at 29 for a hose (not shown). This pipe is connected with the tube 16 and is provided with a suitable valve 30. I next call attention to the spiral fins 31 on the lower half-portion of the shaft 15, these coacting with the shaft and the surrounding tube 13 to form a two-way pump; that is, a pump which feeds the water in and which also sucks the water out, this depending on the direction of rotation of the propulsion shaft 15.

It is evident that the revolving apertured basket arranged in concentric relation to and surrounding the central stationary pump and jet spray means is one important phase of the invention. Equally if not more important is the ways and means of using a single pump and feeder pipe arrangement for both filling and emptying the tub. The centrifugal principle of the basket swirling the water through the orifices in the basket against the ribs 21 in the tub, and the central upper half 18 of the tube 13 coacting therewith, in conjunction with the pump means is thought to be novel.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. A clothes washing machine of the class described comprising a portable relatively stationary tub, an apertured basket confined for rotation within the limits of said tub, means for supporting the basket interposed between the bottom of the tub and the bottom of the basket, said basket being provided with a plurality of circumferentially spaced horizontally disposed spider arms, said arms connected at their outer ends to the upper rim of the basket, a toothed collar connected to the inner ends of said spider arms, an electric motor supported beneath said tub, a shaft connected and rising vertically from said motor and extending up through the bottoms of the tub and basket, said shaft being provided at its upper end with a collar and above said collar with a toothed pinion, said pinion being tapered and fitting in the first collar and engaging the teeth of said first collar, whereby to utilize the shaft, pinion, first named collar and spider arms to drive and rotate said basket.

2. A clothes washing machine of the class described comprising a portable relatively stationary tub, an apertured basket confined for rotation within the limits of said tub, means for supporting the basket interposed between the bottom of the tub and the bottom of the basket, said basket being provided with a plurality of circumferentially spaced horizontally disposed spider arms, said arms connected at their outer ends to the upper rim of the basket, a toothed collar connected to the inner converging ends of said spider arms, an electric motor supported beneath said tub, a shaft connected and rising vertically from

said motor and extending up through the bottom portions of the tub and basket, said shaft being provided at its upper end with a collar and above said collar with a toothed pinion, said pinion being tapered and fitting in the first collar and engaging the teeth of said first collar, whereby to utilize the shaft, pinion, first collar and spider arms to drive and rotate said basket, and a perpendicular water delivery and draining tube concentrically surrounding said shaft and having its upper end apertured and embracing the shaft collar beneath said pinion, the lower half portion of said tube being imperforate and extending down through and beyond the bottom portions of the basket and tub and being supported on said motor.

3. A clothes washing machine of the class described comprising a portable relatively stationary tub, an apertured basket confined for rotation within the limits of said tub, means for supporting the basket interposed between the bottom of the tub and the bottom of the basket, said basket being provided with a plurality of circumferentially spaced horizontally disposed spider arms, said arms connected at their outer ends to the upper rim of the basket, a toothed collar connected to the inner converging ends of said spider arms, an electric motor supported beneath said tub, a shaft connected and rising vertically from said motor and extending up through the bottom portions of the tub and basket, said shaft being provided at its upper end with a collar and above said collar with a toothed pinion, said pinion being tapered, fitting in and meshing with the teeth of said first collar, whereby to utilize the shaft, pinion, first collar and spider arms to drive and rotate said basket, a perpendicular water delivery and draining tube concentrically surrounding said shaft, having its upper end apertured and embracing the second-named collar beneath said pinion, the lower half portion of said tube being imperforate and extending down through and beyond the bottom portions of the basket and tub and being supported on said motor, and a water delivery and emptying pipe beneath the bottom of the tub and connected to the lower adjacent portion of said tube, said pipe being provided with a valve, said pipe being adapted to accommodate a hose for both delivering and draining water, and the lower half portion of said shaft being provided with spiralling pump forming fins, said fins fitting snugly in the imperforate portion of said tube, said tube having drain holes in the otherwise imperforate portion located between the bottom of the tub and bottom of the basket, and said basket having an enlarged drain coacting with said drain holes.
